UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

DRIVING DEVICE.

Application filed October 2, 1919. Serial No. 327,966.

To all whom it may concern:

Be it known that I, JOSEPH H. POPE, a citizen of the United States, residing at Hamilton, in the county of Essex and State 5 of Massachusetts, have invented certain Improvements in Driving Devices, of which the following description, in connection with the accompanying drawings, is a specification, like reference characters on the drawings indicating like parts in the several figures.

The present invention relates to driving devices, and particularly to those employed for attaching heels to shoes. In some types 15 of shoe heels, as the Louis, the central portion is so contracted that when nails are driven from the heel-seat end, as is common in attaching wood heels; parallel to the vertical axis of the heel, the points emerge 20 from the sides, especially at the rear, unless the nails are considerably removed from the edge, in which case there is a tendency for the work to gap at the rand crease. To avoid these difficulties, it is desired in this 25 class of work to start the nails into the heels at an angle to the axis, they more or less closely paralleling the inclination of the sides. This permits them to be brought nearer to the edge of the heel-seat, yet kept 30 within the body of the heel. To enable the nailing to be performed in this manner, an object of the invention is to furnish a driving device which will act at an angle to that at which the driving force is applied.

In accomplishing this purpose, a feature 35 of the invention resides in a driving member of sufficient flexibility to change its inclination as it is guided in its driving action. This flexible member, which I have especially 40 designed for the insertion of nails, is preferably provided by a helix. To one extremity of the member I have herein shown connected a rigid actuating member, and at the other a contact member, by which the 45 nails are driven. Such an arrangement not only permits the attainment of the angular driving thrust, but is also capable of exerting tension to free itself from the work.

A further feature of the invention consists 50 in a novel arrangement of inner and outer members acting together to produce a driving effect. One of these members, preferably the outer, may be flexible, being in the present instance shown as furnished

by the helix previously mentioned; while the 55 inner member includes rigid portions which may be arranged in a series. These rigid portions, or plugs, I prefer to have transmit the driving thrust from the actuating member at one end of the helix to the contact 60 member at the other end. With a driver thus organized, the inner and outer members give mutual reinforcement and will flexibly transmit heavy driving thrusts 65 without distortion.

In the accompanying drawing illustrating a particular embodiment of my invention,

Fig. 1 is a vertical section through the work-support and driving mechanism of a 70 heel-attaching machine; and

Fig. 2 is a similar view, enlarged, through the upper portion of a driver.

The numeral 10 designates a jack or work-support for a shoe, indicated at S, which is 75 to have its heel H attached by nails N driven from within the shoe. In a plate 12 mounted at the top of the jack are openings 14 arranged in accordance with the positions which the nails are to occupy in the 80 heels. Through these openings and below the plate extend guide tubes to receive drivers operating upon the nails. Each tube includes a portion 16 located in one of the 85 openings 14, this portion being inclined from the vertical in the direction in which the nails are to enter the heel, and a portion 18 depending vertically below the plate, these parts 16 and 18 being connected by a 90 thread, indicated at 20. Rising vertically from the usual reciprocatory driver plate, as illustrated in the patent to Standish, dated June 18, 1918, No. 1,269,654, are driver rods 95 22 entering the guide tube portions 18. Each driver rod at its upper end has a reduced portion 24, and surrounding this, preferably sweated to it and resting upon the shoulder between the main and reduced portions, is a helical spring 26 of such length that it extends near the upper portion 18 100 of the tube. The external diameter of the spring approximates the internal diameter of the tube portion 18, it fitting so that it will move readily in the tube without lateral play. The convolutions of the helix are 105 preferably closely placed, they being in actual or substantial contact. At the upper extremity the spring 26 carries a plug, which

may have at its lower portion a stem 28, this being also preferably sweated to the spring, and above this a disk-shaped head 30 resting upon the top of the spring with 5 its edge close to the interior wall of the guide tube. Between the rod and the contact plug is an alined series of relatively short plugs or thrust members 32, these extending in practically unbroken contact between the reduced portion 24 of the rod and the stem 28 of the terminal plug, they fitting closely within the cylindrical interior of the spring. The adjacent ends of the plugs and 10 also the inner ends of the rods and the terminal plug stems are preferably rounded, as is shown at 34, permitting the elements to rock easily upon one another, without tilting wholly upon one edge with a tendency to widely separate the opposite edge. 15

20 The nails N are supplied to the driving devices by inserting them in the portions 16 of the guide tubes, their heads resting upon the contact heads 30 of the drivers. As the latter rise in the driving action and emerge 25 from the tube portions 18 into the inclined portions 16, the springs, on account of their great flexibility, turn at the junctures of the portions without binding; while the change of direction of movement of the plugs 32 30 is facilitated both by the rounded contour of their ends and by the slight entrance of the edges of these ends between the convolutions of the springs, though they are effectively held against material lateral displacement. When the nail points reach the heel, 35 the driving effect necessary to thrust them through the sole into the heel may be transmitted from the rods by both the plugs and springs, though preferably chiefly through 40 the former. They drive the nails into the heel at angles determined by the inclination of the tube portions 16. When the drivers are withdrawn after completing the insertion of the nails, any tendency of the plugs 45 to stick is counteracted by the spring, which, through the terminal plug, positively moves the entire plug series to their normal positions.

Having described my invention, what I 50 claim as new and desire to secure by Letters Patent of the United States is:

1. In a machine of the class described, a member having a guide passage with portions inclined with respect to one another, 55 and a unitary flexible driving member movable in the passage and bending in its passage from one inclined portion to another.

2. In a machine of the class described, a driving device comprising a helical member 60 arranged to transmit the driving impact in a direction inclined to the direction of application of such impact.

3. In a machine of the class described, a driving device comprising a helical member, 65 a member for contact with the work situated

at one extremity of the helix, and an actuating member connected at the other extremity of the helix, the contact member and actuating member being separated and arranged to permit the helix to bend laterally. 70

4. In a machine of the class described, a member having a guide passage with portions inclined with respect to one another, a rigid actuating member situated in one portion of the passage, and a unitary flexible member connected to the rigid member and being movable into another portion of the passage. 75

5. In a machine of the class described, a driving device comprising an inner and an outer member acting simultaneously upon a single object to transmit the driving effect. 80

6. In a machine of the class described, a driving device comprising a flexible member and a device having successive rigid portions surrounded and retained in place laterally by the flexible member, and a guide extending throughout the length of the driving device. 85

7. In a machine of the class described, a reciprocal driving device comprising a cylindrical member and a series of contacting members within said cylindrical member, and a guide surrounding the cylindrical member and in which it is arranged to reciprocate. 90

8. In a machine of the class described, a driving device comprising a flexible cylindrical member and a series of contacting rigid members within said cylindrical member, and a tube in which the flexible member is movable. 100

9. In a machine of the class described, a driving device comprising a helical member, and a series of thrust members situated within the helix and supported laterally thereby. 105

10. In a machine of the class described, a driving device comprising a resilient, helical member, and a series of alined members situated within the helix, both said helix and the inner members being arranged to transmit the driving force. 110

11. In a machine of the class described, a driving device comprising a helical member, and a series of alined thrust members situated within the helix and having adjacent curved extremities contacting to transmit the thrust. 115

12. In a machine of the class described, a driving device comprising a helical spring, and a series of thrust members situated within the spring. 120

13. In a machine of the class described, a driving device comprising a helical spring, and a series of thrust members situated within the spring, a portion of the members being secured to the spring. 125

14. In a machine of the class described, a driving device comprising a helical spring, and a series of thrust members situated 130

within the spring, the terminal members of the series being secured to the spring.

15. In a machine of the class described, a driving device comprising a rod, and a flexible member secured to the rod and arranged to receive and transmit longitudinally the driving force.

16. In a heel-attaching machine, a nail-driver comprising a rod, and a helical spring secured to the rod and arranged to transmit the driving force longitudinally of the rod and from it to the object to be driven.

17. In a heel-attaching machine, a nail-driver comprising a rod, a helical spring secured at one end to the rod, and a plug secured to the opposite end of the spring, the spring co-operating with the rod and plug to transmit the driving force.

18. In a heel-attaching machine, a nail-driver comprising a rod, a helical spring secured at one end to the rod, a plug secured to the opposite end of the spring, and a series of plugs between the terminal plug and rod.

25. 19. In a machine of the class described, a driving device comprising a rod, a helical spring secured at one end to the rod, a plug secured to the opposite end of the spring, and a series of plugs having contacting

rounded ends and situated between the terminal plug and rod.

20. In a machine of the class described, a driving device comprising a helical spring, and a member having a stem within the spring and a head extending over the end of the spring and contacting with the work to apply the driving pressure.

21. In a machine of the class described, a driving device comprising a rod having a reduced portion, a helical spring surrounding the reduced portion, and a terminal member having a stem within the spring at the opposite extremity from the rod and a head extending over the end of the spring and arranged to transmit the driving force.

22. In a machine of the class described, a driving device comprising a rod having a reduced portion, a helical spring surrounding the reduced portion and terminating thereat, a terminal member having a stem within the spring at the opposite extremity from the rod and a head extending over the end of the spring, and a series of plugs lying between the rod and terminal member.

In testimony whereof I have signed my name to this specification.

JOSEPH H. POPE.
